UNITED STATES PATENT OFFICE.

EUGENE T. TURNER, OF NEW YORK, N. Y., ASSIGNOR TO AMERICAN PLAYER ACTION COMPANY, OF NEW YORK, N. Y., A CORPORATION OF WEST VIRGINIA.

ADJUSTABLE ACTION FOR PIANO-PLAYERS.

1,169,441.

Specification of Letters Patent. Patented Jan. 25, 1916.

Application filed November 21, 1913. Serial No. 802,229.

To all whom it may concern:

Be it known that I, EUGENE T. TURNER, a citizen of the United States, residing in the city, county, and State of New York, and whose post-office address is No. 2595 Third avenue, New York city, have invented new and useful Improvements in Adjustable Actions for Piano-Players, of which the following is a specification.

10 In my Patent No. 1,028,308, June 4, 1912, I have described an arrangement of wind chest, pneumatic and piano action for pneumatic piano players designed to permit easy adjustment of the relation of the pneumatic mechanism with the piano action.

15 The present invention relates to a mechanism for securing a similar result with certain advantages of convenience in construction and in use referred to in detail herein-
20 after.

The accompanying drawings illustrate an embodiment of the invention.

Figure 1 is a transverse vertical section of the mechanism showing the pneumatics and the stickers of the piano action in side elevation and the shoes in section. Fig. 2 is a front elevation of the same.

Referring to the embodiment of the invention illustrated the pneumatic mechanism comprises a series of wind chests A arranged one above the other, a slight distance in front of the stickers B which communicate motion to the hammers of the piano in any usual or suitable way. These stickers operate upon the hammers by an upward movement and are held against any substantial amount of horizontal movement.

Upon the backs of the wind chests A are the several pneumatics C each arranged in line with one of the stickers B and having a movable member D which is pivoted upon its lower edge and is adapted to be swung inward when the proper valve mechanism in the wind chest is operated. The movement of the pneumatic is communicated to its sticker by means of an approximately horizontal arm E fastened to the movable member D of the pneumatic near its hinge and projecting rearwardly so as to bring its rear end under a shoe attached to the sticker. To secure a proper co-action between the movable member of the pneumatic and the piano action a nice adjustment of the relation be-

tween the arm E and the shoe on the sticker is necessary.

The principal purpose of this invention is to provide for such adjustment by making the shoe on the sticker movable through a device which is easily accessible and operable from the front of the apparatus. The shoe F, provided with a felt G, is pivotally mounted on the sticker B; the pivot pin H being carried in a block J which is screwed at a proper elevation upon the sticker. The contact end of the shoe is rounded as shown 65 and the shoe may be swung slightly up and down about its pivot in order to secure the desired adjustment. For this purpose the shoe is connected to a downwardly extending arm K, the lower end of which is engaged by a collar or shoulder L on a screw M which extends in a substantially horizontal direction in line with the space between the pneumatics C to which it belongs and that in the next lower row; the threads of the 75 screw extending into the sticker B, so that as the screw is turned it brings the shoe F down upon the arm E of the pneumatic and effects the desired adjustment. The screw in the position described is capable of easy 80 engagement by the socket of a long screw driver which fits the screw head. An operator, therefore, standing at the front of the action can readily adjust the shoes on the stickers to bring them into proper engagement with the pneumatics. The locating of the adjusting device on the sticker, which is practically immovable horizontally, permits a quicker adjustment than with my previously patented device, in which the 85 adjusting screw was on a movable member of the pneumatic, and, therefore, might yield to the pressure of the adjusting screw driver. The adjusting device is entirely in the rear of the pneumatics and operating arms E so 90 that it may have whatever vertical movement is necessary. The vertical space between successive pneumatics C, however, need only be sufficient to admit the blade of the screw driver and should register with 95 the adjusting screw when the sticker is in its lowest position.

What I claim is:—

1. Piano-player mechanism including in combination stickers, pneumatics in front of 105 said stickers and having movable members

adapted to operate the stickers and means for effecting an adjustment of the relative positions of the contacting parts of the stickers and their pneumatics, said adjusting means comprising screws attached to the stickers, extending horizontally, and located, when the stickers are at rest, in line with spaces between the pneumatics so as to be readily accessible for adjustment from the front.

2. The combination with stickers and pneumatics of a player piano, of means for effecting an adjustment of the relative positions of the contacting parts of the stickers and the pneumatics, said adjusting means comprising a shoe carried by the sticker and adapted to be engaged by the movable member of the pneumatic, and an adjusting device for said shoe including a horizontal

screw screwing into the sticker and means for transmitting the movement of said screw to said shoe to adjust the latter vertically.

3. Means for effecting an adjustment of the relative positions of the contacting parts of the stickers and the pneumatics of a piano player comprising a shoe pivotally mounted on the sticker, an approximately vertical arm K connected to said shoe, and a screw M having a threaded engagement with said sticker and having a shoulder engaging said arm.

In witness whereof, I have hereunto signed my name in the presence of two subscribing witnesses.

EUGENE T. TURNERY.
